CLAIM

The ornamental design for an office cubicle wall hanger, as shown and described.

DESCRIPTION

FIG. 1 is a top view of my design of office cubicle wall hanger.

FIG. 2 is a perspective view thereof.

FIG. 3 is a side view thereof (The left and right side views are mirror images.)

FIG. 4 is a front view thereof; and,

FIG. 5 is a bottom view thereof.

The office cubicle wall hanger is a two-pronged hanger that fastens onto the typical fabric covered office cubicle wall, and includes a hook onto which the user can hang a picture, clock, or other items.

The main characteristics of the design for the office cubicle wall hanger is a rectangular shape with a protruding hook, and two sharp pointed prongs.
